ALEKCEI EVGENEVITCH SHEREMETEFF, OF OSNABRUCK, GERMANY.

MEANS FOR OPERATING AND CONTROLLING RAILWAY POINTS, SIGNALS, BARRIERS,
AND THE LIKE.

Application filed May 22, 1923. Serial No. 640,634.

To all whom it may concern:

Be it known that I, ALEKCEI EVGENEVITCH SHEREMETEFF, a citizen of Russian Socialist Federal Soviet Republic, residing at 5 Hotel Schaumburg, Osnabruck, Germany, have invented certain new and useful Improvements in the Means for Operating and Controlling Railway Points, Signals, Barriers, and the like, of which the following 10 is a specification.

This invention relates to improvements in the means for operating and controlling railway points, signals, barriers, and the like.

The power for operating or controlling 15 railway points and the like from a distance has hitherto been taken from a power station or accumulator where power is produced or stored by means separate from the points, members or the like to be operated. 20 In accordance with the present invention the power for operating the points, signals or the like is produced by the trains that travel over or past the point or mechanism to be operated. To this end a power receiving member (such as a ramp or shoe) 25 or members is (or are) provided which is (or are) operated directly by the wheels of a railway vehicle and adapted to transfer power from the vehicle to a power accumulator positioned near the operated member. Means are also provided for controlling 30 from a distance the power stored in the accumulator so as to cause it to effect any desired point setting, signaling, or barrier actuating operation or the like.

The unequal shocks or impulses, to which the power receiving ramp is subjected when passed over by the wheels of a train, are caused to tension an elastic medium such as 40 a spring which, when it is untensioned, yields up its energy to a power accumulator.

Another feature of the invention consists in a motion transferring member which is locked against return movement and, in its 45 forward movement, transfers the motions, due to the power impulses produced by passing trains, to a driving pulley, which latter raises a weight by means of an endless flexible member (such as a chain) or a differential gear.

Due to this locking of motion transferring member the ramp automatically drops as soon as the accumulator is charged.

Still another feature of the invention comprises means by which the power stored

by raising a weight is used for actuating a crank drive whose speed of operation is regulated by a suitable brake mechanism or damping device.

With these general statements of the object and purposes of my invention I will now proceed to describe the embodiment thereof and the manner in which my invention is carried out, and it will be understood that while I have described what may be considered as a preferable embodiment of my invention, I do not limit myself to the precise conditions and arrangements herein set forth, as they may be varied by those skilled in the art in accordance with the particular purposes for which they are intended, and the conditions under which they are to be utilized.

The invention is shown by way of example in the drawing applied to a mechanically operated and electrically controlled point setting device of a railway system.

Figure 1 is a sectional elevation showing one rail and the operating mechanism, and

Figure 2 is a diagrammatic view, partly 50 in plan and partly in elevation, showing the operating mechanism.

In the drawing *a* is a ramp extending along the outside edge of a rail. The top surface of the ramp is slightly higher than the head of the rail so that it is depressed by each wheel that runs over it. The ramp is pressed upward through levers and a rod *d* by means of a pressure spring *b* which is compressed whenever a wheel runs over the ramp. The ramp, which is depressed by each wheel to an extent which equals the amount of its elevation above the head of the rail, is returned by the spring *b* to its normal position the moment the wheel has passed over it, the extent of upward movement of the ramp being limited by two suitable stops.

At each restoration of the ramp to its raised or normal position, the energy imparted to the spring in compressing it is transferred to a power storing device or accumulator. The means for transferring the power from the ramp to the power accumulator consists of a movable pawl *c* or the like adapted to be moved by the power transferring rod *d*. When the spring *b* is compressed the pawl *c* is non-operative, but when the spring *b* is untensioned the pawl *c* rotates a ratchet driving wheel *e*. Each 105 110

time the ramp *a* is released after being depressed by a wheel, the pawl *c* turns the driving pulley *e* through an equal angular distance.

Attached to the driving pulley *e* is an endless chain which passes round a driving pulley *e*¹, so as to form a loop *k*, and around a second pulley so as to form a second loop *l*. The chain also passes around an operating pulley *h*. The two loops *l* and *k* are tensioned by weights *m* and *n*, *m* serving to pull down the loop *l* when the weight *n* is raised by means of the driving pulley *e*¹.

The operating pulley *h* is locked in its normal position by an electromagnetically controlled detent *s* so that the section of chain which passes round the pulley *h* is held immovable during the shortening of the loop *k* and the simultaneous lengthening of the loop *l* due to the operation of the pawl *c*, by which the driving pulley *e* is rotated in the direction of the arrow shown thereon.

It will thus be seen that the winding up of the point-moving or operating weight *n* is not effected by the sudden shocks or depressions of the ramp *a*, but by the untensioning of the spring *b* that is compressed at each depression of the ramp. Hence the forward motions of the pawl *c* due to the untensionings of the spring *b* are uniform or rhythmical.

The gravity stored in the raised operating weight *n* is the energy available for operating the points, signals or the like. The dropping of the weight *n* is normally prevented by the holding pawl *g* of the driving pulley *e* and the electromagnetic detent *s* of the operating pulley *h*. It is by the pulley *h* that the positions of the points, signals and the like are changed as required. Combined with the pulley *h* is a crank *i* which is turned clockwise or always in the same direction through an angle of 180° at each point setting operation and thus oscillates the point actuating levers and rods.

These turning movements of the disk *h* are controlled by the detent *s* and projections or stops *r*, *r*¹ which are displayed by 180° with respect to each other on the circumference of the pulley *h*. The pull exerted on the loop *k* by the operating weight *n* tends to rotate the operating pulley *h* clockwise, but in the position of the part shown in the drawing the pulley *h* is locked against rotation by the projection *r* striking against the detent *s*. When the latter is released by an electromagnet so that its lower end moves out of the path of the projection *r*, the pulley *h* rotates clockwise until the other projection *r*¹ strikes against the detent *s* which by this time will have been oscillated into its normal position, as by a spring. The pulley *h* with the crank *i* have now executed one half of a revolution and

the point setting rods and levers have also executed corresponding movements by which the point has been moved from its normal into its reversed position, that is the position in which it lies close to the main rail. During these point closing operations the section of the chain coiled round the driving pulley *e* is kept fixed by the detent *g* and the length of chain that travels over the operating pulley *h* must therefore be paid out by the loop *l* so that this loop is shortened while the loop *k* is lengthened. Hence the weight *m* will be raised to the same extent as the operating weight *n* is lowered.

At each succeeding oscillation of the detent *s* the operating pulley *h* turns clockwise through an angle of 180° and moves the point setting levers and rods in the opposite direction to that in which they were turned by the previous half turn of the pulley *h* and its associated crank *i*.

The speed of revolution of the crank *i* set up by the sudden operation of the weight *n* is damped or regulated by a liquid or air brake *q* which is linked to the pulley *h* in such a way that a retarding action of similar character is exerted during each half turn of the crank. This retarding effect is greatest at the commencement and conclusion of each half turn of the crank, but is considerably smaller at the middle of each half turn, when it is desirable to allow the driving weight to exert its full force.

A spring coupling *p* is connected in the point moving rod, this coupling being adapted to compensate for small changes of length due to fluctuations of temperature. The elastic coupling *p* will thus always pull the point into close contact with the main rail. A coupling which yields sufficiently to allow the closed point to be swung away from the main rail by the action of a wheel flange passing between the main rail and the point, but which does not yield when the point is closed by the point operating mechanism, may also be connected in the point operating rod.

As the driving weight cannot be raised indefinitely it may reach its highest point before all the wheels of the train have passed over the ramp. The first wheel that passes over the ramp after the weight *n* has been raised to its highest position will compress the spring *b* and swing back the pawl *c*, but the pulley *e* will now remain fixed so as to keep the pawl back and prevent the untensioning of the compressed spring *b*. Hence the ramp *a* will remain depressed so that the remaining wheels of the train exert no effect on the ramp and its associated mechanism.

If the power be stored in a pneumatic or hydraulic accumulator the ratchet and pawl mechanism and mechanical power transmit-

ting elements are replaced by an air pump or liquid pump which forces air or liquid into a suitable container when the spring is compressed by means of the ramp is un tensioned. The compressed air or liquid in the container may even be used to operate several pneumatic or hydraulic devices controlled from a distance by means of electro-magnetic controlling gear.

10 I claim:-

1. In combination with a railtrack of a vehicle, a power accumulator consisting of a suspended weight, a power receiving member extending along a rail and arranged to be subjected to the direct impact-action of a wheel of a passing vehicle, a spring interposed between said power receiving member and said power accumulator for absorbing the impact-action of a wheel imparted upon said power receiving member and permitting the charging of said accumulator by the energy of the said spring only, and means for controlling from a distance the power stored in the accumulator.

2. In combination with a railtrack of a vehicle, a power accumulator, a power receiving member, a spring, a motion transferring means, a locking member arranged to be controlled by the said motion transferring means and free to automatically resist the restoration of said power receiving member when the accumulator is fully charged, and means for controlling from a distance the power stored in the accumulator.

3. In combination with a railtrack of a vehicle, a power accumulator, a power receiving member, a spring connected at one end with the said power receiving member having the other end fixed to an unmovable body, a motion transferring means connected

with the movable end of said spring, a locking member for keeping the accumulator non-operative within the duration of an impact-action of a passing wheel and for allowing the said accumulator to become receptive for a charge synchronously with the raising motion of said power receiving member, and electrical means for controlling from a distance the power stored in the said accumulator.

4. In combination with a railtrack of a vehicle, a ramp depressible by the wheels of a vehicle, a spring, a member connected to the ramp for tensioning the said spring, a pulley, a weight raisable by the said pulley, a member for rotating the pulley when the spring is untensioned, a point, a flexible member pulled by the said weight, a second pulley rotatable by the said weight, a crank connected to the second pulley for moving the said point, and means for controlling from a distance the action of the said crank on the said point.

5. In combination with a railtrack of a vehicle, a ramp depressible by the wheels of a vehicle, a spring, a member connected to the ramp for tensioning the said spring, a pulley, a weight raisable by the said pulley, a member for rotating the pulley when the spring is untensioned, a point, a flexible member pulled by the said weight, a second pulley rotatable by the said weight, a crank connected to the second pulley for moving the said point, means for controlling from a distance the action of the said crank on the said point, and a retarding device for damping the movements of the said crank.

In testimony whereof I affix my signature.

ALEKCEI EVGENEVITCH SHEREMETEFF.
